UNITED STATES PATENT OFFICE.

JOSEPH H. NIQUETTE, OF LOS ANGELES, CALIFORNIA, AND E GEORGE SANDERS, OF GALVESTON, TEXAS.

DESIGN FOR A COMBINED FOOD AND BEVERAGE VENDING STATION.

Application filed August 14, 1928. Serial No. 27,810. Term of patent 14 years.

To all whom it may concern:

Be it known that we, JOSEPH H. NIQUETTE and E GEORGE SANDERS, citizens of the United States, residing at Los Angeles and Galveston, in the county of Los Angeles and Galveston, and State of California and Texas, respectively, have invented a new, original, and ornamental Design for a Combined Food and Beverage Vending Station, of which the following is a specification, reference being had to the accompanying drawings forming a part hereof:

Figure 1 is a front elevation of our new design for a food and beverage vending station, with a canopy enclosing the vending area.

Figure 2 is a front elevation of our new design, with the doors in the canopy in open position.

Figure 3 is a diagrammatic top plan view of the design on a somewhat reduced scale.

We claim:

The ornamental design for a combined food and beverage vending station substantially as shown.

Signed at Los Angeles, California this 31 day of July, 1928.

JOSEPH H. NIQUETTE.
E GEORGE SANDERS.
